UNITED STATES PATENT OFFICE.

KENNETH C. BROWN, OF EVANSTON, AND RAYMOND E. WHITE, OF CHICAGO, ILLINOIS,
ASSIGNORS TO WINSLOW SAFETY HIGH PRESSURE BOILER COMPANY, OF CHI-
CAGO, ILLINOIS, A CORPORATION OF ILLINOIS.

BURNER.

Application filed February 5, 1923. Serial No. 616,912.

Our invention relates to liquid fuel burners, particularly of the atomizing type. The present design of burner has been developed for automotive work, such as the heating of high pressure steam boilers for the propulsion of pleasure cars, busses, trucks and tractors. In this field, the operation of the burner is necessarily intermittent because of the variable character of the load. 10 Intermittent operation is frequently provided for through the use of a pilot burner which is maintained lit during the entire operating period of the boiler for the purpose of igniting the main volume of combustible mixture when the latter is introduced into the combustion chamber. The maintenance of one of these pilot burners has heretofore presented a considerable practicable difficulty. If the pilot burner is 20 vaporizing in principle it is incessantly clogging up from depositions of carbon in the vaporizing passages. If the pilot burner is atomizing in principle, through the use of an electric motor and air blower, the 25 continuous running of the electric motor entails a considerable drain on the storage battery, and the noise of the motor is objectionable.

One of the particular objects of the present invention is to provide burner mechanism in which the main burner is atomizing in principle through the use of an electric motor and blower, but in which the pilot burner is atomizing in principle through the 35 use of a jet of steam from the boiler. A further object is to provide an arrangement of pilot burner and main burner whereby the blast from the pilot burner nozzle assists in the aspiration and atomization of the fuel 40 from the main burner jet.

A further object is to preheat the air for the main burner, as by passing it through a conduit which is subjected to heat from the combustion chamber.

45 A further object is to provide an improved construction of reducing valve for reducing the pressure of the steam supplied to the pilot nozzle.

Referring to the accompanying drawings 50 in which we have illustrated a preferred embodiment of our invention;

Figure 1 is a diagrammatic layout of the invention, illustrating the combustion chamber in section.

Figure 2 is a similar side elevational view, 55 the illustration of the combustion chamber being a section taken on the plane of line 2-2 of Figure 1.

Figure 3 is a view similar to Fig. 1 of a modified arrangement. 60

Figure 4 is a vertical sectional view through the pressure regulating by-pass valve employed in Fig. 1.

Figure 5 is a similar view of the main burner nozzle. 65

Figure 6 is a longitudinal sectional view of our improved pressure reducing valve.

Figure 7 is another sectional view at right angles to Figure 6.

Figure 8 is a horizontal sectional view 70 taken on the plane of line 8-8 of Figure 6.

Figure 9 is an enlarged detail view of the removable valve seat employed in the foregoing reducing valve, and

Figure 10 is a longitudinal sectional view 75 through the pilot burner nozzle.

The combustion chamber or fire pot 15 is of cylindrical form, having an outer circular wall composed of one or more layers of heat refractory and heat insulating materials. The combustible mixtures are injected tangentially into this combustion chamber through an inlet passageway 16. The outer end of this conduit is threaded for screwing into a coupling sleeve 17, 85 which receives at its other end the threaded end of an elbow 18. The sleeve 17 has a laterally extending port 19 which is normally closed by a removable plug 21; removal of this plug affording an igniting opening 90 through which a match, torch or other flame can be inserted into the mixture passageway for initially lighting the burner mechanism. 95

The outer end of the elbow 18 is provided with a threaded flange 22 into which screws a coupling member 23 which connects the end of the main air conduit 24 with the elbow 18. The air conduit 24 is extended around a considerable portion of the fire pot 15 in contact therewith so that the heat from the fire pot will have a preheating effect on the air before its admixture with the liquid fuel. This preheating portion 24' is expanded vertically to provide a large surface of inner wall in contact with the inner refractory wall of the fire pot 15. This section of the air conduit is riveted or other- 100 105

wise fastened to the outer metallic shell of the fire pot, as indicated at 25. A diagonal intake 26 connects through a section of flexible conduit 27 with a tapered hood 28 fitting over the discharge connection 29 of the blower 31. This blower is driven by an electric motor 32, which is included in an automatically governed circuit, the opening and closing of which is responsive to pressure fluctuations in the boiler 33. This automatic control circuit will be described presently.

The fuel supply for the main burner is drawn from a main supply tank diagrammatically represented at 34 in Figure 2. The fuel is fed to the main burner under pressure obtained from a spur gear pump 35, one gear element of which is mounted directly on the motor and blower shaft 36. The intake connection for the pump 35 leads from the bottom of the supply tank 34; the outlet from the pump 35 is through pipe 37 and T connection 38 to the pipe 39 leading to the main fuel nozzle 41 discharging in the elbow 18. A pressure controlled by-pass circuit is provided in shunt of the pump 35 so as to maintain a predetermined discharging pressure upon the fuel supplied to the nozzle 41. This by-pass circuit comprises a short section of pipe 42 branching the other way from the T connection 38 and communicating with the intake passageway 43 of a by-pass valve 44. Extending from the outlet port 45 of this valve unit 44 is a pipe 46 which discharges into the top of the main supply tank 34. As shown in Figure 4, the valve housing 44 has a longitudinal bore connecting the inlet and outlet passages 43 and 45, and in this longitudinal bore is formed a tapering valve seat 47. A ball valve 48 seats downwardly on this valve seat 47, a compression spring 49 tending to hold this valve on the seat in opposition to the pressure of the fuel from the pump 35. An adjusting screw 51 screws into the top of the longitudinal bore and provides adjustable means for varying the pressure of the spring 49, a lock nut 52 serving to hold the screw 51 in any adjusted position. The gear pump 35 is of the proper capacity to pump a slightly greater volume of oil than is required at the main nozzle 41, or is capable of issuing therefrom, and this excess volume is by-passed through the by-pass valve unit 44. The pressure of the spring 49 opposing this by-pass flow maintains a uniform, steady pressure on the fuel supplied to the main nozzle 41.

Referring to the nozzle structure illustrated in Figure 5, it will be observed that the nozzle 41 screws up into the under side of the elbow 18, directly in the line of discharge from the pilot nozzle 53. The lower end of the nozzle 41 is enlarged and threaded internally as indicated at 54 to receive the

upper threaded end of a check valve housing 55. A ball check 56 normally tends to seat on a tapering valve seat 57 in this housing under the pressure of a spring 58. The fuel pipe 39 screws into the bottom of this check valve housing 55 and discharges against the under side of the ball check 56. The ball check 56 is a precautionary element serving a number of purposes. The spring 58 is of sufficient pressure so that if the gravity or pressure head from the supply tank 34 should leak past the gear pump 35 this gravity or pressure head would be insufficient to unseat the ball check 56 and cause a discharge of fuel from the nozzle 41 with the burner inert. Similarly, this spring pressed check valve prevents premature or after burning with insufficient air by virtue of its action of retarding or interrupting the fuel flow except at high blower speeds when there is sufficient air for combustion. The ball check 56 of course opposes a smaller retarding force to the flow of fuel than does the by-pass valve 48. The pilot burner nozzle 53 is mounted in a boss 59 extending rearwardly from the elbow 18 so as to discharge in the line of the tangential inlet 16. The details of this pilot burner nozzle are illustrated in Figure 10. The steam is discharged through an outer sleeve 59 having a converged discharge outlet 61. The outer end of this sleeve is threaded at 62 for receiving the fitting 63 to which connect the steam pipe 64 and fuel supply pipe 65. The steam pipe 64 discharges into a cavity 66 communicating with the rear end of the outer sleeve 59. An inner sleeve 67 extends forwardly from the fitting 63 and discharges in close proximity to the tapered outlet port 61. The comparatively small discharge opening 68 in the end of this inner sleeve is controlled by a needle valve 69 which screws into the outer end of the fitting 63 at 71 and has an adjusting handle 72 for its manipulation. The fuel supply pipe 65 connects through a suitable coupling 73 with a passageway 74 opening into the rear end of the inner sleeve 67.

The fuel supplied to this pilot burner through pipe 65 may be the same fuel which is supplied to the main burner nozzle 41, such as kerosene or other fuel of comparatively low volatility; or the fuel may be of higher volatility, such as gasoline, in which latter case the fuel would be drawn from a separate supply tank. Because of the pronounced atomizing and vaporizing effect of the blast of high temperature steam it is entirely practicable to employ fuels of comparatively low volatility in this pilot burner nozzle and accordingly we supply fuel therefrom to the same source supplying the main burner. The pipe 65 extends over and connects with the underside of the tank 34, the arrangement being such that a gravity or

pressure flow is supplied from this tank to the pilot nozzle. A hand valve 76 is interposed in this pipe line at a point of convenient access to the driver, so that this pilot burner can be turned off and on.

Referring to Figure 1, the steam supply pipe for this pilot nozzle has connection with a T 77 on each side of which are mounted hand valves 78-79. The valve 78 controls communication between the pipe 64 and a nipple connection 81 adapted for receiving the end of a hose leading from a source of compressed air. The vehicle is preferably provided with a tank of compressed air so that the pilot burner can be set into operation by an air blast when there is no steam in the boiler. This is accomplished by connecting the compressed air lead over the nipple 81, closing the valve 79, and opening the valve 78. In this connection we wish to remark that the fluid pressure nozzle 53 can be operated by compressed air throughout the entire operating interval of the nozzle without recourse to steam at any time; or the nozzle can be operated alternately by air and steam; or both fluids may be admitted to boost the action of the nozzle.

A steam supply pipe 82 extends from the valve 79 to the boiler 33. Interposed in this steam supply pipe is a hand valve 83 for turning the pilot burner off and on, and an automatic pressure reducing valve 84 for reducing the high boiler pressure (from 300 to 1500 pounds) to a more desirable pressure or use at the pilot nozzle. We have successfully operated this pilot nozzle on steam pressures ranging from 5 to 10 pounds.

This great drop of pressure requires a sensitive, reliable pressure reducing valve. Because of the very high boiler pressure any leaks or irregularities of operation in the reducing valve will result in a disturbed burner operation and a loss of steam. In Figures 6, 7, 8 and 9 we have illustrated a reducing valve which is capable of effecting this large reduction and is efficient and reliable in operation. The housing 85 has an inlet boss 86 and an outlet boss 87. A diaphragm 88 closes the upper part of the chamber 89 and is secured to the housing 85 by a flanged cap 91. The inlet steam is conducted through a tubular arm 92 extending inwardly to the center of the chamber 89, and thence the steam is passed downwardly through a tapering restricted nozzle 93. The emission of steam from the nozzle 93 is controlled by the position of a nozzle seat 94 which is suspended from the diaphragm 88 so as to rise and fall with the flexure of the diaphragm. This nozzle seat consists of a threaded plug having a recess 95 in its upper end, which recess is slightly beveled to provide a narrow tapering valve seat for the nozzle 93. This plug 94 screws into the cross hub 96 of a stirrup which engages over

the sides of the nozzle and is locked by a nut 94'. The upper end of the stirrup 97 bears against the under side of the diaphragm 88 and has a threaded stud 98 passing up through the diaphragm for receiving the flanged nut 99 bearing against the top of the diaphragm. A compression spring 101 bears against the nut 99, and at its upper end reacts against a collar 102 which is adapted for vertical adjustment through the provision of the adjusting screw 103 having the operating handle 104. The bottom of the housing 85 is closed by a plug 105 which is removable for adjustment of the interior parts, such as of the plug 94, draining the valve chamber, etc.

It will be noted that there is no guiding connection between the lower wall of the plug or housing and the stirrup 97. As a result of this arrangement, the nozzle seat 94 has a universally inclinable mounting, in that the diaphragm 88 will flex to permit inclination of the stirrup and nozzle seat in any direction. Thus, the nozzle seat 94 is always capable of inclining laterally in any direction or shifting laterally so as to accurately center the recess 95 over the end of the nozzle 93. We have found the use of Monel metal in the construction of the nozzle 93 and nozzle seat 94 successful in maintaining a steam tight joint against the relatively high temperature and pressure under which the present system works. The diaphragm 88 is preferably of copper.

The operation of this pressure reducing valve will be obvious, it being evident that when the pressure in the chamber 89 falls below the minimum predetermined by the pressure of the spring 101 the diaphragm 88 will fall under this spring pressure and within the nozzle seat 94 from the nozzle 93, thereby admitting more steam until the desired maximum pressure is obtained, when this pressure will become effective under the diaphragm 88 and draw the nozzle seat 94 back against the nozzle 93.

The operation of the motor 32 for driving the main burner blower is controlled by a pressure governed circuit controller 107 which has connection with the boiler 33 through pipe 108. This circuit controller may be of the construction disclosed in the co-pending application of Raymond E. White, Ser. No. 615,774 filed January 29, 1923. The device 107 controls the primary or winding circuit 109 of the relay 111. The contacts 112 of the relay control a secondary or motor circuit 113. A storage battery 114 supplies current to both circuits 109 and 113. A few turns of the motor circuit 113 are preferably superposed on the winding of the circuit 109 so as to assist in holding the contacts in firm engagement after they have been drawn together, but these turns are not sufficient to lock up the relay.

In Fig. 1 the front leaf springs of the vehicle are indicated at 115, from which it will be noted that the fire box of the burner is located centrally of the frame with respect to the sides thereof and is dropped down between the springs and into proximity to the front axle. The diagonal air connection 26 and intervening section of flexible conduit 27 is intended to dispose the blower 31 and motor 32 on the running board of the vehicle, or in a compartment located where the running board is usually situated.

In Fig. 3 we have shown an arrangement dispensing with the spur gear pump 35 for obtaining the pressure feed to the main burner nozzle; obtaining the requisite feeding pressure by air pressure imposed upon the fuel in the supply tank 34. In this instance, the fuel supply line 39' is led directly from the lower part of the tank 34 to the main burner nozzle 41, and an electrically actuated valve is interposed in this fuel line for opening and closing the line in response to the actuation of the motor 32. As illustrative of such a valve, a conical valve 118 is arranged to seat on a tapering valve seat 119 in a valve housing 121. A stem 122 extends from the valve 118 out of the housing 121 and supports a core or armature element 123 which reciprocates in a solenoid 124. A spring 125, assisted by the pressure on the fuel, tends to hold the valve seated. The winding of the solenoid 124 is included in series with the circuit 113 of the blower motor 32, so that energization of the blower motor will result in opening of the valve 118, and will maintain this valve open as long as the motor is being operated. A hand valve 126 is also included in the fuel line 39'. The desired air pressure may be built up in the tank 34 by a hand pump 127, or any power actuated pump.

It should be observed that the combination of the air blower for the main burner and the steam or air nozzle for the pilot burner have a particular cooperative relation. In the operation of the main burner the steam jet from the pilot nozzle exerts an aspirating action on the main burner nozzle 41 and vaporizes and atomizes the fuel therefrom by virtue of the temperature and velocity of this steam jet. The blower supplies the requisite volume of air for combustion and assists in this atomization. Because the air is not the sole atomizing agent its velocity can be regulated through a wide range in the present burner, if such regulation is desired.

We do not intend to be limited to the particular details herein shown and described, except as they are defined in the appended claims.

We claim:

1. In burner mechanism adapted for heating boilers and the like, the combination of a combustion chamber, main burner mecha-

nism comprising a blower, an electric motor for driving said blower, and a fuel port discharging liquid fuel into the air stream of said blower, said main burner mechanism supplying the requisite volume of mixture for heavy firing, and secondary burner mechanism discharging into said combustion chamber and comprising a steam nozzle adapted to receive steam from said boiler, and a fuel port for introducing liquid fuel into the jet of steam from said nozzle.

2. In burner mechanism for heating boilers and the like, the combination of a combustion chamber, a blower, a fuel nozzle adapted to discharge liquid fuel into the air stream from said blower, an electric motor for actuating said blower, an electric circuit for said motor comprising automatic control mechanism whereby said blower is operated intermittently in accordance with the firing requirements of the boiler, and a steam jet adapted to be supplied from said boiler and discharging into said combustion chamber for producing the desired atomization and vaporization of the liquid fuel during the non-operating interval of said blower.

3. In combination, a boiler, a combustion chamber for heating said boiler, a blower discharging into said combustion chamber, an electric motor for actuating said blower, automatic mechanism for setting said motor into operation when the pressure in said boiler reaches a predetermined point, a steam nozzle discharging a jet of steam into said combustion chamber, a pipe connecting said steam nozzle with said boiler, valve means in said pipe for controlling the pressure of the jet of steam discharged from said nozzle, and fuel supply means adapted to mix liquid fuel with the blast of air from said blower and with the jet of steam from said nozzle.

4. In combination, a boiler, a combustion chamber for heating said boiler, an air conduit discharging into said combustion chamber, a blower connected to said air conduit, an electric motor for actuating said blower, automatic circuit control mechanism for said electric motor for setting said motor into operation during predetermined conditions of said boiler, a fuel nozzle in the path of the air blowing through said air conduit, a steam nozzle discharging a jet of steam across the tip of this fuel nozzle, and a connection between said steam nozzle and said boiler comprising a reducing valve.

5. In combination, a boiler, a combustion chamber for heating said boiler, an air conduit discharging into said combustion chamber, a blower connected to said air conduit, an electric motor for actuating said blower, automatic circuit control mechanism for said electric motor for initiating operation thereof when the pressure in said boiler falls below a predetermined minimum, a main fuel nozzle disposed in said air conduit, a

steam nozzle for discharging a jet of steam across the tip of said main fuel nozzle, a pipe connecting said steam nozzle with said boiler, a reducing valve in said pipe, and a 5 secondary fuel nozzle for mixing fuel with said jet of steam.

6. In burner mechanism, in combination with a steam boiler, of a combustion chamber for heating said boiler, said combustion chamber being of circular form, a mixture 10 passageway entering said chamber tangentially, a main fuel nozzle projecting into said mixture passageway, an air conduit discharging into said mixture passageway, a blower 15 supplying said air conduit, a pilot nozzle discharging substantially axially of said tangential mixture passageway and across the tip of said main fuel nozzle, said pilot nozzle comprising inner and outer sleeves, means 20 for admitting a fluid under pressure to one of said sleeves, and means for admitting liquid fuel to the other of said sleeves.

7. In combination, a steam boiler, a combustion chamber associated therewith, main 25 burner mechanism including a conduit through which an air blast is supplied to the end chamber, and means for introducing a stream of liquid fluid into the said conduit, the said main burner mechanism supplying the requisite amount of mixture for 30 relatively heavy firing, means for rendering the said main burner mechanism inoperative when the pressure of the steam in the boiler exceeds a predetermined amount, secondary burner mechanism discharging into 35 the said conduit of the main burner mechanism constantly during the operation of the said combustion chamber and including means for projecting a jet of steam from 40 the boiler into the said conduit, and means for introducing liquid fuel into the jet of steam, the said jet of steam serving to atomize and vaporize both the stream of liquid fluid of the main burner mechanism and the liquid fuel of the 45 secondary burner mechanism.

8. In combination, a steam boiler, a combustion chamber associated therewith, a conduit communicating with the said chamber, 50 means for forcing a blast of air through the said conduit into the chamber, a liquid fuel nozzle discharging into the said conduit, a second nozzle in back of the said first nozzle for projecting a jet of steam and fuel into the conduit across the tip of the fuel nozzle, 55 the said jet of steam and fuel serving to atomize and vaporize the liquid fuel discharged into the conduit by the first nozzle, and means controlled by the pressure of the steam in the boiler for automatically cutting off the air blast and the supply of liquid fuel to the first nozzle when the pressure exceeds a predetermined amount, the said second nozzle being constantly in use during 60 the operation of the combustion chamber and serving as a pilot burner.

the said jet of steam and fuel serving to atomize and vaporize the liquid fuel discharged into the conduit by the first nozzle, means controlled by the pressure of the steam in the boiler for automatically cutting 65 off the air blast and the supply of liquid fuel to the first nozzle when the pressure exceeds a predetermined amount, the said second nozzle being constantly in use during 70 the operation of the combustion chamber and serving as a pilot burner, and means for automatically controlling the pressure of the steam jet supplied to the second nozzle.

9. In combination, a steam boiler, a combustion chamber associated therewith, main 75 burner mechanism including a conduit through which an air blast is supplied to the said chamber, and means for introducing a stream of liquid fluid into the said conduit, the said main burner mechanism supplying the requisite amount of mixture for 80 relatively heavy firing, means for rendering the said main burner mechanism inoperative when the pressure of the steam in the boiler exceeds a predetermined amount, and 85 secondary burner mechanism discharging into the said conduit of the main burner mechanism constantly during the operation of the said combustion chamber and including means for projecting a jet of fluid into 90 the said conduit, and means for introducing liquid fuel into the jet of fluid, the said jet of fluid serving to atomize and vaporize both the stream of liquid fuel of the main burner mechanism, and the liquid fuel of the 95 secondary burner mechanism.

10. In combination, a steam boiler, a combustion chamber associated therewith, a conduit communicating with the said chamber, 100 means for forcing a blast of air through the said conduit into the chamber, a liquid fuel nozzle discharging into the said conduit, a second nozzle in back of the said first nozzle for projecting a jet of steam and fuel into 105 the conduit across the tip of the fuel nozzle, the said jet of steam and fuel serving to atomize and vaporize the liquid fuel discharged into the conduit by the first nozzle, and means controlled by the pressure of the steam in the boiler for automatically cutting off the air blast and the supply of liquid fuel to the first nozzle when the pressure exceeds a predetermined amount, the said second nozzle being constantly in use during 110 the operation of the combustion chamber and serving as a pilot burner.

In witness whereof, we hereunto subscribe our names this 29th day of January, 1923.

KENNETH C. BROWN.
RAYMOND E. WHITE.
